(57) **CLAIM**

The ornamental design for a utility cart as shown and described.

DESCRIPTION

FIG. 1 is a perspective view of a utility cart showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of an indicated portion of FIG. 1;

FIG. 9 is another perspective view showing a drawer with the utility cart; and,

FIG. 10 is the other perspective view showing drawers with the utility cart.

The broken line portions of the utility cart in FIGS. 1-10 represent unclaimed portions of the claimed design and form no part thereof. The broken line portions of the drawers in FIGS. 9-10 represent unclaimed portions of the claimed design and form no part thereof. The do lines in FIGS. 1 and 8 demarcate the boundary of the FIG. 8 enlarged view of the claimed design and form no part thereof.

1 Claim, 10 Drawing Sheets
